UNITED STATES PATENT OFFICE.

JOHN BAUMANN, OF GLEASON, WISCONSIN.

DESIGN FOR A COMBINED BOTTLE-OPENER AND BUTTON-HOOK.

47,096.

Specification for Design.

Patented Mar. 16, 1915.

Application filed September 1, 1914. Serial No. 859,714. Term of patent 7 years.

To all whom it may concern:

Be it known that I, JOHN BAUMANN, a citizen of the United States, residing at Gleason, in the county of Lincoln and State of Wisconsin, have invented a new, original, and ornamental Design for Combined Bottle-Openers and Button-Hooks, of which the following is a specification, reference being had to the accompanying drawing, forming a part thereof.

The figure is a perspective view of a combined bottle opener and button hook, showing my new design.

I claim:

The ornamental design for a combined bottle opener and button hook, as shown.

JOHN BAUMANN.

Witnesses:

CONRAD GERBIG,
ANTON BAUMANN.
